1 Claim. (Cl. 315—106)

ABSTRACT OF THE DISCLOSURE

A high leakage reactance transformer is provided with a primary winding, a high voltage secondary winding, and a third winding magnetically coupled to the second winding for supplying filament voltages in an electron discharge device. Because of the significantly high leakage reactance of the transformer, the load current supplied by the high voltage secondary winding affects the voltage output of the third winding. Thus the filament or heater voltage in a high voltage electron discharge device is a direct function of the load current flowing through the tube.

Background of the invention

(1) *Field of the invention.*—This invention relates to power supplies and more particularly to an automatic filament voltage controlling system for a thermionically operable vacuum tube.

(2) *Description of the prior art.*—In thermionically operable electron discharge devices employing high voltage anodes and electron emissive filaments or cathodes, it is often desirable to control the cathode heater current in accordance with the magnitude of the anode current being drawn. In certain types of electron emissive devices such as conventional vacuum tubes, it may be desirable to provide increasing filament voltages with increasing magnitudes of anode current being drawn. In other types of devices, such as the magnetron, the life characteristic of the cathode is deleteriously affected by overheating, an effect directly related to back bombardment of the cathode by the electrons under high anode current load conditions. The latter situation optimumly requires that the cathode temperature be held constant under increased load situations.

Efforts to control the cathode heater current in accordance with the device load current has resulted in elaborate arrangements utilizing relays, servo systems, manual potentiometers, and other similar and expensive types of control systems. One proposed alternative to the foregoing has been to provide a cathode assembly structure of two dissimilar metals having varying thermal coefficients of expansions. By suitable placement of contacts, expansion and contraction of the thermal elements control the application of voltage to the heater, thereby maintaining the cathode within a safe operational temperature range. However, the principal disadvantage of the foregoing arrangement is the necessity of having to construct a bimetallic heater element as an integral portion of any tube in which it is necessary to control the cathode heater current.

It is therefore a prime object of this invention to provide a circuit arrangement which will regulate the electron emissivity of any thermionically operable electron discharge device. It is a further object of this invention to provide an automatic control system for varying cathode heater current in accordance with the degree of anode current in an electron discharge device.

It is another object of this invention to reduce the harmful effects of high operating cathode temperatures in magnetron tubes by reducing cathode heater current under conditions of increasing anode current.

2

Summary of the invention

In accordance with the foregoing objects, the present invention utilizes a leakage reactance transformer having a primary winding, a secondary high voltage winding and a third winding magnetically coupled to the secondary high voltage winding and having sufficient turns to provide suitable heater current for an electron discharge device of either the conventional or the magnetron variety. The leakage reactance transformer has the property of allowing an added voltage build-up across the filament supply winding in proportion to the magnitude of current flowing in the high voltage winding. By properly arranging the filament voltage winding, increases in current flowing through the high voltage winding can have the effect of either raising or lowering the voltage appearing across the filament winding. In this manner, filament voltage control becomes a factor directly dependent upon the degree or magnitude of current flowing through the high voltage winding.

Brief description of the drawings

FIG. 1 is a schematic illustration of a conventional electron discharge device provided with a stand-by filament voltage in accordance with this invention; FIG. 2 is another embodiment of the invention schematically illustrating a magnetron being provided with automatically controllable filament voltage in accordance with the present invention; FIG. 3 schematically illustrates the voltage relationships of the arrangement of FIG. 2.

Description of the preferred embodiments

Referring to FIG. 1 there is shown a transformer core constructed of a suitable magnetic material and having a plurality of magnetic flux paths defined by transformer legs 12, 13 and 14. The transformer leg 12 includes a non-magnetic series gap 15 which represents a relatively high leakage reactance path with respect to legs 13 and 14 and requires a relatively high magnetizing force to approach saturation or to highly magnetize the gap. The transformer leg 14 includes a primary winding 16 coupled to a source of alternating current power 17. Transformer leg 13 includes a secondary high voltage winding 18 and a further secondary winding 19 having a number of turns in relation to the primary windings sufficient to supply proper filament voltage to an electron discharge device illustrated as a conventional vacuum tube 20. The high voltage secondary winding 18 is coupled through a capacitor 21, a rectifier 22, and a load resistance 23 to the anode 24 of the discharge device 20. The further secondary winding 19 is coupled to a filament 25, while a cathode 26 is coupled to the other polarity terminal of the rectifier 22. In operation, because of the relatively high magnetizing force required to saturate the transformer core 10, an increasing load current drawn through the output load terminal 27 of the electron discharge device 20 will result in increased current through the secondary winding 18. The resulting increased magnetic flux flowing through the transformer legs of secondary winding 18 and the magnetically coupled winding 19 will result in an increased voltage appearing at the output of the secondary winding 19. Decreasing load currents will have the opposite effect.

The arrangement of FIG. 1 is designed to be self regulatory with regard to variations in supply voltage. The leakage reactance of the transformer 10 and the reactance of the capacitor 21 are chosen to be theoretically equal in impedance magnitude at a frequency above line frequency. At line frequency, the effective impedance of the secondary circuit will exhibit a capacitive rather than inductive characteristic. If the supply voltage should vary, for example to a higher value than is designated, an increasing current begins to flow into the transformer pri-

3

mary 16. The resulting increase in magnetic flux causes a decrease in effective leakage reactance. Since the capacitive reactance remains unchanged, the total secondary impedance will undergo a net increase. The increase of secondary impedance acts to reactively compensate for the line voltage increase and thereby maintain the current flow to the load constant. Thus, a balancing effect is achieved and current flow stabilized.

Referring to FIG. 2, a similar arrangement to that disclosed for FIG. 1 is described in connection with controlling the filament voltage applied to a magnetron 28. In this arrangement transformer core 29 is provided with an additional filament voltage control winding 30 which is connected in series with a conventional filament voltage control winding 31. Windings 30 and 31 have been placed on the core 29 in magnetically opposite senses. As shown in FIG. 2, E_a represents the voltage output from the winding 30; E_b represents the voltage output from the winding 31, and E_f represents the algebraic sum of the voltages E_a and E_b as applied to the filament of the magnetron 28. Referring now to FIG. 3, under no load conditions, winding E_a will provide a voltage of a first magnitude and winding E_b a voltage of second and opposite magnitude, resulting in a third voltage E_f , representing the algebraic difference between the voltages E_a and E_b , being applied to the filament of the magnetron. As the load increases (lower half of FIG. 3) current flowing through the secondary high voltage winding 32 of the transformer core 29 of FIG. 2 will increase, thereby increasing the voltage E_b produced at the output of winding 31. The resultant voltage E_f is thereby decreased. In this manner an automatic mode of operation results in decreasing the filament voltage applied to a magnetron with increases of load current through the magnetron, thereby eliminating the deleterious effects of overheating.

Although several embodiments of the invention have been shown and described, it will be apparent to those skilled in the art that various changes and modifications may be made therein without departing from the scope of the invention as defined by the appended claim.

I claim:

1. In combination with a loadable electron discharge device having no load to full load operating current conditions and including a high voltage electrode and a thermionically emissive element, an automatic voltage

regulation system for adjusting the voltage applied to said thermionically emissive element inversely with the change in load current flow magnitude to said high voltage electrode, comprising, a transformer core having a plurality of legs, one of said legs including a nonmagnetic gap for imparting a significant leakage reactance characteristic to said core, a first winding coupling a first leg of said transformer core to a source of alternating line current power, a second winding coupled to a second leg of said transformer core, a third winding having a first half coupled to said first leg and a second half coupled to said second leg, said first and second halves series coupled in voltage opposing senses, said third winding coupled to said thermionically emissive element for supplying voltage thereto, a capacitor having a reactive impedance substantially equal to the reactive impedance of said core leakage reactance at a frequency above the frequency of said line current source, means connecting said capacitor between said second winding and said high voltage electrode, said capacitor and said leakage reactance forming a first total impedance at no load and a second total impedance at full load, said second total impedance being greater in magnitude than said first total impedance, thereby maintaining magnetic flux in said first leg relatively constant from no load to full load conditions, said second leg having increased magnetic flux from no load to full load conditions, thereby raising the voltage level induced across said second half of said third winding, the net voltage appearing across both halves of said third winding thereby decreasing from no load to full load conditions, and thereby decreasing the current applied to said thermionically emissive element.
